UNITED STATES PATENT OFFICE.

WILLIE J. FAIRBANK, OF SOLDIER, KANSAS.

DOOR-FASTENER.

No. 915,576.

Specification of Letters Patent. Patented March 16, 1909.

Application filed June 8, 1908. Serial No. 437,407.

To all whom it may concern:

Be it known that I, WILLIE J. FAIRBANK, a citizen of the United States, residing at Soldier, in the county of Jackson and State of 5 Kansas, have invented certain new and useful Improvements in Door-Fasteners; and I do declare the following to be a full, clear, and exact description of the invention, such as will enable others skilled in the art to 10 which it appertains to make and use the same.

My invention relates to door or gate fasteners.

The object of the invention is to provide a 15 strong, simple and durable fastening device which can be easily applied to the door or gate and which can be sold at a comparatively low cost.

A further object of the invention is to provide 20 a fastener of this character which may be changed at a minute's notice from a fastener for use on right hand doors to a fastener for use on left hand doors, or for a fastener to be used in connection with sliding 25 doors.

With these and other objects in view, the invention consists of certain novel features of construction, combination and arrangement of parts, as will be more fully described 30 and particularly pointed out in the appended claims.

In the accompanying drawings, Figure 1 is a top plan view of the device applied to a sliding door, Fig. 2 is a rear elevation, Fig. 3 is a vertical section on the line 3—3 of Fig. 1, Fig. 4 is a plan view of a device applied to a 35 swinging door, Fig. 5 is a rear elevation thereof, Fig. 6 is an enlarged detail top plan view of the device shown in Fig. 4.

40 Referring more especially to the drawings, and especially to Figs. 1 to 3, 1 represents the door and 2 the jamb or frame therefor. The door is provided with three vertically aligned apertures 3, 4 and 5, the intermediate 45 one being considerably larger than the first and last mentioned apertures, and being adapted to receive the shank of the operating member 6. Secured to the front side of the door by bolts 7 and 8, which pass through 50 the apertures 3 and 5 respectively is the front or escutcheon plate 9, which receives and bears the enlarged head 10, of the operating shank which carries the handle 11. The rear of the shank is supported by a plate

or collar 12, also held in position upon the 55 door 1 by the bolts 7 and 8. This collar is provided with an enlarged neck 13 so as to receive the spiral operating spring 14, whose ends are engaged respectively with the pin 15 carried on the collar 12, and with a lateral 60 lug 16, projecting inwardly from the latching member 17, adjacent the inturned handle end 18. The latching member is keyed to the shank 6 by a set screw 19, and is provided at one end with right angular latch extension 65 20, which is adapted to ride up upon the inclined face 21, of the keeper 22, and which is engaged in the notch 23. When it is desired to change the device so as to be utilized upon a door running in an opposite direction 70 it is simply necessary to reverse the latch member 17 and the spiral spring.

In the modification shown in Figs. 4, 5 and 6, the keeper 24 is held upon the inside of the jamb 25, and a latch member 26 rides up 75 over its inclined surface and falls into the notch as is usual. The latching member in this instance is provided with a handle end 27, similar in all respects to the handle 18, and the opposite end instead of being made 80 at right angles to the line of the latch member is made perfectly straight and has a flat side as at 28. The projection 13 of the collar 12 is provided with a notch at 29 which is engaged by the lug 30 on the latching member 85 so as to limit the movement of the latter.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of 95 this invention as defined in the appended claims.

Having thus described my invention what I claim and desire to secure by Letters Patent is:

1. In a fastening device, the combination with an operating shank, of a rotating latching member adjustably connected to the shank, resilient means to hold said latching member from rotation, and means whereby 105 said latching member may be reversed.
2. In a fastening device, the combination with an operating shank, of means for jour-

naling the shank in a door or gate, an interchangeable latching device adjustably connected to the shank, resilient means to normally prevent the shank and latching device from rotating, and means to limit the movement of the shank and latching device in both directions.

In testimony whereof I have hereunto set my hand in presence of two subscribing witnesses.

WILLIE J. FAIRBANK.
